FRANK E. WELLMAN, OF KANSAS CITY, KANSAS, ASSIGNOR TO THE KANSAS CITY GASOLINE COMPANY, OF KANSAS CITY, MISSOURI, A CORPORATION OF KANSAS.

STILL OR RETORT.

1,245,291.

Specification of Letters Patent.

Patented Nov. 6, 1917.

Application filed February 23, 1915. Serial No. 9,880.

To all whom it may concern:

Be it known that I, FRANK E. WELLMAN, a citizen of the United States, residing at Kansas City, in the county of Wyandotte 5 and State of Kansas, have invented certain new and useful Improvements in Stills or Retorts; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to stills or retorts, and more particularly to a device of this character adapted for the distillation, or cracking, of compounds, such as hydrocarbon oils; the principal object of the invention being to provide a still wherein fractionation 20 of the vapors resulting from the compounds acted upon may be accomplished at definite temperatures.

A further object of the invention is to 25 provide a method of distilling that is economical in operation and wherein the pressure, ordinarily used during the distilling of compounds, is unnecessary.

In accomplishing these objects I have provided 30 a closed vessel for receiving the oil to be distilled and from which vapors are driven into a superheater and then into a condenser for definite fractionation; which latter is accomplished by means of outlets 35 at intervals along the condenser coil.

The preferred form of structure is herein-after described and illustrated in the accompanying drawings, wherein:—

Figure I is a vertical section of a still 40 embodying my invention.

Fig. II is an enlarged vertical section of the thermometer setting and valve parts.

Referring more in detail to the drawings:—

45 1 designates an ordinary furnace provided with a boiler, or the like, 2, for receiving the compound for distillation.

Opening from the upper portion of the boiler 2 and leading into a furnace 3 is a 50 pipe line 4; the said pipe being formed into a coil 5 within the furnace to present a large amount of heating surface so that vapors passing into the coil are quickly superheated; the heating being accomplished 55 by means of a gas burner 7, as shown, or by any other suitable means such as a

bath of some heated, non-volatile substance, whereby contents of the coil may be heated to the required temperature, which varies usually from 750 to 850 degrees Fahrenheit, 60 according to the kind of liquid under treatment.

Connected with the lower end of the superheating coil 5 and leading from the furnace 3 to a condenser 8 is an upwardly 65 inclined pipe line 9.

Branching from the line 9, intermediate the furnace coil and condenser 8 is a return pipe 10 which extends through the upper part of the boiler 2 and delivers into the 70 liquid in the boiler, so that vapors condensed before reaching the condenser may flow back to the boiler for a second heating.

The condenser 8 preferably comprises a casing 12 having inlet and outlet pipes 13— 75 14 through which a cooling fluid may pass.

Mounted within the casing 12 are a plurality of coils, 15, 15'—15"; the said coils being a continuation of the pipe 9, and placed at intervals along said coil are outlet 80 pipes, 16, 16'—16" which lead to a line 17; each of said outlets being provided with a valve 18, 18'—18", and intermediate each of said coils 15 is a cut-off valve 19, 19'—19".

Mounted within each of the outlet pipes 85 16 is a thermometer 20, 20'—20" which projects through a bushing 21, 21'—21" so that it may be read by the still tender; the bulb being extended back into the coil so that the exact temperature of the vapor at that point 90 may be known.

The pipe line 17 has its lower terminal at the boiler 2 so that condensed vapor may flow back for a second action, the upper end leading to a water-cooled condenser 22 containing a water-cooled coil 23 wherein all vapor remaining in the line is condensed.

Presuming the parts to be constructed as described, oil or petroleum to be cracked is placed in the boiler and heat applied to the 100 boiler in order to effect vaporization. Vapors rising from the oil or petroleum pass through the boiler outlet into the superheater coil where additional heat is applied and the temperature of the vapor raised to 105 usually from 750 to 850 degrees Fahrenheit; the superheating acting on the vapors to break up and crack the molecules without materially increasing pressure within the coil owing to the fact that the superheater 110 coil has a free opening to the atmosphere through the outlet of the condenser.

The vapor, after passing through the superheater, flows up through the pipe 9 into the fractional condenser; the pipe being arranged at an incline so that any condensation liquid will flow back along the pipe to the return pipe 10 through which the liquid is redelivered into the liquid in the boiler for a second treatment, while the vapor is delivered to the first coil of the fractional condenser.

10 When the vapor passes into the first condenser coil from the pipe 9, it is cooled and the less volatile vapors reduced to liquid which may flow through the remaining coils 15 of the condenser or are drawn off through the first branch 16 when the first condenser coil is cut off by its valve 19.

If the still is to be operated for collecting a member of the compound that vaporizes 20 and condenses at a relatively high temperature, say 450 degrees Fahrenheit, the first unit of the condenser only is used; the upper or first unit coil being cut off from the rest of the condenser by its valve 19, and the 25 valve 18 to the main condenser opened so that vapor passing into the fractional condenser will travel through the first coil and out through the branch 16 into the pipe 17 where the uncondensed vapor passes on to the condenser coil 23 where it is condensed 30 into the desired liquid, any liquid condensing in the pipe passing back to the boiler through the return portion of the pipe.

Should it be desired to save a member of 35 the compound that condenses only at a lower temperature, the first valve 19 is left open and the valve 18 closed so that the vapors must pass through the first and second units and be reduced to a lower temperature, say 40 350 degrees Fahrenheit. For saving the latter liquid the second valve 19' is closed and the second valve 18' opened so that vapors passing through the two coil units are delivered into the pipe 17 through which the 45 uncondensed vapors pass into the final condenser and any condensation liquid is returned to the boiler as before.

It is apparent that the fractional condenser may be provided with as many units 50 as may be necessary or desirable for the reduction of the compound to the several elements of which it is composed; the condition and action of the fractional condenser being noted and controlled by the operator who 55 may note the temperature in the condenser by means of thermometers and govern the operation accordingly.

Having thus described my invention, what I claim as new therein and desire to secure 60 by Letters-Patent, is:

1. The combination with a vaporizer, of a condenser and a fractionator interposed between them comprising separate, connected units, means for conducting vapor from 65 the vaporizer to the first of said units, means

for cutting off flow from one condenser unit to the next, a branch pipe for drawing off contents from each of said units at a point opposite its intake, and an off-take pipe common to and communicating with the several branch pipes, having one end leading upward to the condenser to carry over vapors to be condensed, and the other end leading downward to the vaporizer to carry back intermediate condensates.

2. The combination with a vaporizer and a condenser, of means for conducting vapor from the vaporizer to the condenser, and a fractional condenser interposed in said conducting means and comprising a plurality of units arranged one above the other, said conducting means from the vaporizer being connected to the upper part of the first unit, and the lower end thereof being connected to the upper end of the next succeeding unit, 85 and so on, a branch pipe connected between each pair of adjacent units, an off-take pipe common to said branch pipes, having one end extending upwardly to the condenser and constituting a portion of the said conducting means, and its other end extending downwardly to the vaporizer to permit intermediate condensates to drain thereinto, and valves in said branch pipes.

3. The combination with a vaporizer, of a fractionator comprising a vertical series of separate connected units, means for conducting vapor from the vaporizer to the uppermost of said units, means for cutting off flow from one condenser unit to the next, an off-take pipe, a branch leading from each of said units to the off-take pipe, a valve in each of said branches, a condenser with means for cooling the same, a pipe line from said off-take pipe leading upwardly to the upper end of said condenser, a second pipe line extending from the lower part of the off-take pipe downwardly to the vaporizer, and means associated with the branch from each unit to determine the temperature of condensation therein.

4. The combination with a vaporizer of a fractionator consisting of a vertical series of connected units, a condenser, an upwardly extending pipe line from the vapor outlet of the vaporizer to the uppermost unit of the fractionator, an off-take pipe connected to the several units of the fractionator and extending upwardly to the upper end of the condenser, means for determining the discharge from one or more of the units of the fractionator into said off-take pipe, and a descending drainage pipe extending from a point on the initial vapor line between the vaporizer and the fractionator, downwardly into the vaporizer.

5. The combination with a vaporizer of a fractionator consisting of a vertical series of connected units, a condenser, an upwardly extending pipe line from the vapor outlet

of the vaporizer to the uppermost unit of the fractionator, an off-take pipe connected to the several units of the fractionator and extending upwardly to the upper end of the 5 condenser, means for determining the discharge from one or more of the units of the fractionator into said off-take pipe, a descending drainage pipe extending from a point on the initial vapor line between the 10 vaporizer and the fractionator, downwardly into the vaporizer, and a second drainage pipe extending from said off-take pipe downwardly into the vaporizer, whereby heavy fractions may be condensed in the 15 vapor line and returned to the vaporizer without reaching the fractionator, while predetermined fractions may be selected and returned to the vaporizer from the fractionator, without interrupting the continuity of 20 the process.

6. A low pressure cracking system comprising a vaporizer, a superheater, a fractionator, and a condenser, serially connected, a pipe line from the vaporizer to the superheater, and an upwardly extending pipe line from the superheater to the fractionator, a plurality of branch pipes from the fractionator with means to control the flow through each of them, a pipe line extending 25 from said branch pipes upwardly to the condenser, a drainage pipe extending downwardly from said pipe line to the vaporizer,

means to heat the vaporizer, means to heat the superheater, and means for cooling the fractionator and the condenser respectively. 35

7. A low pressure cracking system comprising a vaporizer, a superheater, a condensing pipe line, a vertically arranged multiple unit fractionator, and a final condenser, serially connected, a pipe line connecting the vapor chamber of the vaporizer with the superheater, said upwardly extending condensing pipe line connecting the superheater to the uppermost unit of the fractionator, valves between the several units of 40 the fractionator, branch pipes connected to said several units above said valves respectively, valves in said branch pipes, an off-take pipe common to said branch pipes and extending upwardly to said condenser, a 45 drainage pipe extending from the lower end of said off-take pipe downwardly to the vaporizer and extending beneath the liquid level therein, and a second drainage pipe extending from an intermediate point on 50 said condensing vapor line, downwardly into the vaporizer and also passing beneath the liquid level therein.

In testimony whereof I affix my signature in presence of two witnesses.
